US00D999083S

(12) **United States Design Patent** (10) **Patent No.:** **US D999,083 S**
(45) **Date of Patent:** **** Sep. 19, 2023**

(54) **BAND ATTACHMENT FOR WATCH**

(71) Applicant: **STEEL AMERICAN LUXURY LLC**,
Winnetka, IL (US)

(72) Inventor: **Nicole Steel**, Winnetka, IL (US)

(73) Assignee: **STEEL American Luxury LLC**,
Winnetka, IL (US)

(**) Term: **15 Years**

(21) Appl. No.: **35/515,657**

(22) Filed: **Oct. 22, 2022**

(80) **Hague Agreement Data**

Int. Filing Date: **Oct. 22, 2022**

Int. Reg. No.: **DM/224872**

Int. Reg. Date: **Oct. 22, 2022**

Int. Reg. Pub. Date: **Nov. 25, 2022**

(51) **LOC (14) Cl.** **11-01**

(52) **U.S. Cl.**

USPC **D11/3**

(58) **Field of Classification Search**

USPC D11/1-6, 94; D10/32

CPC G04B 37/14; G04B 37/05; G04B 37/0058

(57) **CLAIM**

The ornamental design for a band attachment for watch, as shown and described.

DESCRIPTION

1. Band attachment for watch
2. Band attachment for watch
- 1.1 : Top front perspective
- 1.2 : Front
- 1.3 : Back
- 1.4 : Right
- 1.5 : Left
- 1.6 : Top
- 1.7 : Bottom
- 1.8 : Bottom back perspective
- 2.1 : Top front perspective
- 2.2 : Front
- 2.3 : Back
- 2.4 : Right
- 2.5 : Left
- 2.6 : Top
- 2.7 : Bottom
- 2.8 : Bottom back perspective

The figures include surface shading, which represents contour and not surface ornamentation; the broken lines shown in the figures illustrate portions of the band attachment for

(Continued)

watch that form no part of the claimed designs; the dot-dash broken line in figure 2.1 represent the boundaries of the claimed design.
